UNITED STATES PATENT OFFICE.

BYERS W. KADEL, OF ROANOKE COUNTY, VIRGINIA.

TRUCK SIDE BEARING.

1,241,396.

Specification of Letters Patent. Patented Sept. 25, 1917.

Application filed August 21, 1916. Serial No. 116,045.

To all whom it may concern:

Be it known that I, BYERS W. KADEL, a citizen of the United States, residing in the county of Roanoke and State of Virginia, have invented certain new and useful Improvements in Truck Side Bearings, of which the following is a specification.

This invention has to do with side bearings for car trucks and the object thereof is 10 to provide an improved arrangement of side bearing and truck-bolster members. With such object in view the invention consists of the formation, combination and arrangement of parts as will be herein described and 15 claimed.

In the drawings, Figure 1 is a broken plan view showing a truck equipped with a side bearing constructed in accordance with the present invention. Fig. 2 is a longitudinal, 20 vertical section of the same, taken substantially on the line 2—2 of Fig. 1. Figs. 3 and 4 are each partial views of the same nature as Fig. 2 and each showing slightly modified forms of the invention.

Referring to these drawings there is 25 shown a truck of the six-wheel type having the usual wheels 1, axles 2 and side frames 3. A truck bolster 4 receives the load from the car body upon a center plate 5 and transfers it to the side frames, axles and wheels. 30 This bolster consists of a longitudinal member 6 and two spaced transverse members 7 and 8, the latter being supported at their ends by the side frames and supporting in 35 turn near their centers the ends of the member 6.

These cross members 7 and 8 are flexible or yieldable with respect to each other on the springs 9 in and out of a horizontal 40 plane. They are preferably constructed of flanged shape in cross section, an I-section being shown in the drawings, with open sides turned facing each other. A side-bearing bar 10 extends from one to the other 45 of these bolster members 7 and 8 and is yieldably supported thereby so as not to interfere with the aforesaid flexibility of the bolster construction. The bar, however, is guided or restrained so that it will not tilt 50 sidewise out of a vertical position, there being coöperating and interengaging guides provided such as 11 on the bolster members and 12 on the side-bearing bar, these being preferably disposed at some distance from 55 the point of support of the side-bearing bar upon the bolster, the better to resist the

tendency of the bar to tilt out of its normal position. The bar is supported on the cross members 7 and 8 between the points of support of these members on the side frames or within the load-carrying zones of the cross bolsters. And I support and guide this bar upon the cross bolsters without materially cutting away the metal of either flange and 60 weakening the members.

This bar is supported upon one set of flanges, either the upper or lower, of the cross bolsters and is guided or held in substantial vertical alinement by suitable means carried by the other flange. Thus in Figs. 1 65 and 2 the ends of the bar 10 extend within the open sides of the transverse bolster members and are supported on the bottom flanges thereof and there are guides 11 cast out from the upper flanges of these cross 70 bolsters to engage coöperating guides 12 on the bar 10 to maintain this bar in its vertical position. In Fig. 3 is shown how an opening may be formed in the vertical web of the 75 I and the ends of the bar 10 carried on a 80 seat 13 so as to bring the side-bearing load central. And in Fig. 4 is shown how the ends of the bar 10 may be supported upon the top flanges of the bolster members and coöperating guides 14 and 15 be formed on 85 the end of the bar and the lower flange of the bolster member respectively. And in 90 none of these forms are the cross bolsters materially weakened by cutting away the flange members.

There are, of course, the usual side bearings 95 16 carried on the side-bearing bar 10, and this may be of any of the customary forms.

Thus I have provided an arrangement of 100 side bearing that overcomes a number of existing difficulties. It will be evident that modifications in construction might be made within the scope of the claims without departing from the spirit of my invention.

What I claim is:

1. In a side bearing for car trucks, a truck bolster having a pair of spaced, transverse, load-carrying members having upper and lower flanges, means for supporting the ends 105 of the same, and means for applying car-body loads thereto between the said supports, a side-bearing bar extending therebetween and supported thereby intermediate the ends of the bolster members and within 110 the load-carrying zones of the same, said bar being supported upon one of said sets

of flanges and there being means carried by the other set for guiding and alining the said bar without materially cutting away the metal of either flange.

5. 2. In a side bearing for car trucks, a truck bolster having a pair of spaced, transverse, load-carrying members having upper and lower flanges and being yieldable with respect to each other in and out of a horizontal plane, means for supporting the ends of the same, and means for applying car-body loads thereto between the said supports, a side-bearing bar extending therebetween and yieldably supported thereby intermediate 10 the ends of the bolster members and within the load-carrying zones of the same, said bar being supported upon one of the said sets of flanges and guided by the other set without materially cutting away the metal 15 of either flange.

20 3. In a side bearing for car trucks, a truck bolster having a pair of spaced, transverse members with upper and lower flanges and with open adjacent sides, a side-bearing bar 25 extending therebetween with its ends extending within the open sides of said bol-

ster members and supported upon the lower flanges thereof, there being coöoperating means carried by the other flanges and the ends of the bar for holding the bar in vertical alinement, and a side bearing on the said bar.

4. In a side bearing for car trucks, a truck bolster having a pair of spaced transverse members with upper and lower flanges, and 35 with open adjacent sides, said bolster members being yieldable with respect to each other in and out of a horizontal plane, a side-bearing bar extending therebetween and yieldably supported upon the lower 40 flanges thereof, there being coöoperating means carried by the upper flanges and the ends of the bar for holding the bar in its normal position, and a side bearing on the said bar.

45 In testimony whereof I affix my signature in the presence of two witnesses.
